(57) **CLAIM**

We claim the ornamental design for a hedge trimmer, as shown and described.

DESCRIPTION

FIG. 1 is a right side elevational view of a hedge trimmer incorporating our new design;

FIG. 2 is a top plan view thereof;

FIG. 3 is a front side elevational view thereof;

FIG. 4 is a rear side elevational view thereof;

FIG. 5 is a bottom plan view thereof; and,

FIG. 6 is a left side elevational view thereof.

The broken lines showing of the cutting blade is for illustrative purposes only and forms no part of the claimed design.
